UNITED STATES PATENT OFFICE

EARL E. EICKMEYER, OF DAYTON, OHIO, ASSIGNOR TO THE NATIONAL RECORDING
PUMP COMPANY, OF DAYTON, OHIO, A CORPORATION OF OHIO

LIQUID-MEASURING PUMP

Application filed January 9, 1925. Serial No. 1,396.

This invention relates to liquid measuring pumps and is designed more particularly for use on gasoline dispensing pumps, such as are commonly employed at filling stations. 5
In certain types of measuring pump, more particularly the single cylinder pumps, the piston is elevated to discharge the measured quantity of liquid from the cylinder and is then released and permitted to move downwardly by gravity. The actuating device for 10 the piston usually comprises a rack and pinion which is connected by a train of gearing with a handle or crank and where the piston is to move downwardly by gravity the handle is detachably connected with the actuating 15 device so that it can be separated therefrom to release the piston for downward movement. The objection to this type of device has been the tendency of the piston to move 20 downward when the pressure on the handle was relieved. If the handle was released without disconnecting it from the piston actuating device it would be rotated in a reverse direction with sufficient force to injure the 25 operator if it struck him, but even if means, such as a pawl and ratchet, are provided to prevent the rearward movement of the handle there would still be some downward movement of the piston, when the handle is released, because of the lost motion between the 30 pawl and the tooth of the ratchet wheel and even though this movement is slight it would in the course of a day's business mean the delivery of a considerable amount of liquid 35 over and above the supposedly measured amounts for which payment had been received. Further, in a pawl and ratchet lock when the rack bar for the piston is moved upwardly against the stop which limits its 40 movement and the pawl drops behind its tooth just at the end of this movement, the handle is held so tight that it is difficult to disconnect the same and thus release the piston. Further, with a device of this kind the 45 piston will sometimes fail to move downward by gravity, due either to the corroding of the gears or to other reasons, and where a pawl and ratchet or similar detent is applied to the handle the latter cannot be operated to 50 force the piston down.

One object of the invention is to provide in a pump of this kind means for positively preventing all reverse movement of the piston when the pressure on the handle is released, so long as the handle is connected with the actuating device for the piston. 55

A further object of the invention is to provide such a device in which the handle will be normally held against reverse movement but may still be operated to force the piston 60 downwardly.

A further object of the invention is to provide such a mechanism which will be simple in its construction and operation and which may be constructed and installed at a relatively low cost. 65

Other objects of the invention will appear as the device is described in detail.

In the accompanying drawings Fig. 1 is a vertical sectional view of a device embodying my invention; Fig. 2 is a transverse sectional view taken on the line 2-2 of Fig. 1; and Fig. 3 is a side elevation of the device. 70

In these drawings I have illustrated one embodiment of my invention and have shown the same as applied to a gasoline dispensing pump of well known character but it will be understood that this particular embodiment has been chosen for the purposes of illustration only and the device may take various forms and may be applied to pumps of various kinds without departing from the spirit of the invention. 75

In the present drawings I have shown only such parts of the pump itself as are necessary to the explanation of the construction and operation of the invention. As here shown, the piston is operated by a toothed rack bar 1 which is connected with, and in effect forms a part of, the piston rod, the piston rod and piston not being shown. This rack meshes with a pinion 2 which is carried by a shaft 3 journaled at its opposite ends in suitable bearings 9 carried by a frame 4. Mounted on the shaft 3 and rigidly connected with the pinion 2 is a gear 5 which meshes with a pinion 6 on a second shaft 7 which is also journaled in suitable bearings 8 mounted in the frame 4. The bearings 8 and 9 are here shown as ball bearings in order to reduce the 80 85 90 95 100

frictional resistance to the operation of the device as far as possible but obviously any suitable bearing may be employed. The actuating device for the piston, that is the train of gearing just described, is connected with an operating handle or crank 10 and this connection is preferably a separable one so that the crank may be connected with the actuating device for the purpose of operating the piston and may be disconnected from the actuating device to permit the latter to rotate in a reverse direction as the piston moves downwardly by gravity. The connection between the crank and the actuating device may take various forms but I have here shown a very simple form of connection in which the crank or handle is provided with a shank 11 supported in a suitable bearing and the adjacent ends of the shank 11 and the shaft 7 are provided with cooperating clutch faces which may be engaged and disengaged by the longitudinal movement of the shank in its bearing. As shown, this shank has in its inner end a recess 12 adapted to receive a tongue or projection 13 carried by the end of the shaft. The shank of the handle is here shown as mounted in a supporting member 14 which in turn is journaled in a bearing 15 carried by a bracket 16 rigidly secured to the frame 4. Preferably the bracket is detachably secured to the frame, as by means of screws 17, so that the mechanism may be assembled thereon as a unit and the bracket then attached to the frame. To prevent the accidental withdrawal of the shank of the crank from its bearing or guideway in the supporting member 14 a stop arm 18 is pivotally mounted on the bracket 16 and provided with a projection or nose 19 arranged in the path of a stop, such as a collar 20, on the shank of the crank or handle. The nose 19 of the stop arm is spaced from the stop collar 20 a distance sufficient to permit the shank to be disengaged from the shaft 11 and when it is desired entirely to remove the shank from the bearing the pivoted arm is moved out of the path of the stop collar on the shank.

The shank of the handle or crank 10 is so mounted in the rotatable support 14 that these two parts are held against relative rotation, this being preferably accomplished by imparting to the shank and its guideway in the supporting member a non-circular shape, these parts being, in the present instance, hexagonal in form. In order to prevent the reverse movement of the handle and consequently of the piston when the handle is connected therewith I have provided a device to prevent the reverse rotation of the supporting member 14, this device being so connected with the supporting structure and handle that it will normally hold these parts against rotation but will permit them to be moved in a reverse direction when pressure

is applied to the handle in a reverse direction. Preferably this device is in the nature of a one-way clutch, one member of which is normally stationary and the other member of which is connected with the supporting member 14 for rotation therewith, the connection being a yieldable one so that when pressure is applied to the handle the supporting structure and handle may be rotated in a reverse direction while the rotatable part of the clutch is held against rotation by the fixed part thereof. In the present construction the bracket 16 is provided at the inner end of the bearing 15 with a cavity or recess 21 and the supporting structure 14 has formed on its inner end an enlargement or head 22 which is rotatably mounted in the cavity 21 and which is provided at its inner end with a circumferential flange 23 which overlaps the bracket 16 and is confined between the same and the frame 4 so as to close the inner side of the cavity. The diameter of the head 22 is less than the internal diameter of the cavity 21, thus providing between the walls of these parts a space and in this space is mounted an annular member 24 which constitutes the rotatable member of the one-way clutch. Cooperating with this annular clutch member is a detent or friction roller 25 which is loosely mounted in a tapered guideway 26 formed in the bracket 16 at one side of the structure and opening into the cavity 21. The recess 26 increases in width in the direction of the forward rotation of the supporting member 14 and crank 10 so that when the crank is operated forwardly the friction roller 25 will be elevated out of frictional contact with the clutch member 24 and the outer wall of the recess 26 and will not interfere with the free forward movement of the clutch ring 24. The recess 26 being arranged in substantially a vertical position the friction roller will move by gravity into frictional contact with the walls of the recess 26, one of which is formed by the clutch ring, as soon as the forward movement of the clutch ring ceases, thereby preventing instantly any reverse movement on the part of the clutch ring. The clutch ring 24 is connected with the supporting member 14 for the crank or handle in such a manner that it will normally rotate therewith but the connection is a yielding one so that when the clutch ring is held against movement the supporting member may be moved relatively thereto. Preferably this connection is a frictional one and, as here shown, a series of plungers 27 are mounted in radial recesses in the head 22 of the supporting member and are pressed outwardly by springs 28 into frictional contact with the inner circumferential face of the clutch ring 24. The frictional contact between these plungers, and the ring is such as to cause the ring to rotate normally with the supporting mem-

ber and to prevent the movement of the supporting member relatively to the clutch ring by the tendency of the piston to move downwardly. Consequently when the handle 10 is released the clutch will operate instantly to check the reverse movement of both the handle and the piston. Should it be desirable, however, to force the piston downwardly, this can be accomplished by applying sufficient pressure to the handle 10 in a reverse direction to overcome the frictional contact between the plungers and the clutch ring. This construction also permits the shank of the handle to be readily adjusted to bring the clutch members 12 and 13 into alinement, and prevents the locking of the shank of the handle against longitudinal movement by the wedging action of the rack bar 1 against the stop.

20 While I have shown and described one embodiment of my invention I wish it to be understood that I do not desire to be limited to the details thereof as various modifications may occur to a person skilled in the art.

25 Having now fully described my invention, what I claim as new and desire to secure by Letters Patent is:

1. In a pump, the combination with a piston actuating device, a rotatable handle, and 30 a connection between said handle and said actuating device, of a structure mounted in fixed relation to said actuating device, comprising a bearing and having an annular cavity at the inner end of said bearing, a sup- 35 port for said handle rotatably mounted in said bearing and having a head arranged in said annular cavity, a clutch ring interposed between said head and the circumferential wall of said cavity, a clutch member arranged 40 to engage said clutch ring and hold the same against movement in one direction, and means for connecting said support with said clutch ring.

2. In a pump, the combination with a piston 45 actuating device, a rotatable handle, and a connection between said handle and said actuating device, of a structure mounted in fixed relation to said actuating device, comprising a bearing and having an annular cavity 50 at the inner end of said bearing, a support for said handle rotatably mounted in said bearing and having a head arranged in said annular cavity, a clutch ring interposed between said head and the circumferential wall 55 of said cavity, a clutch member arranged to engage said clutch ring and hold the same against movement in one direction, and a frictional connection between said support and said clutch ring.

60 3. In a pump, the combination with a piston actuating device, a rotatable handle, and a connection between said handle and said actuating device, of a structure mounted in fixed relation to said actuating device, com- 65 prising a bearing and having an annular cav-

ity at the inner end of said bearing, a support for said handle rotatably mounted in said bearing and having a head arranged in said annular cavity, a clutch ring interposed between said head and the circumferential wall 70 of said cavity, a clutch member arranged to engage said clutch ring and hold the same against movement in one direction, plungers slidably mounted in the head of said support and springs for forcing said plungers into 75 frictional engagement with said clutch ring.

4. In a pump, a frame, a piston actuating device mounted on said frame and comprising a shaft, a handle having a shank, said shaft and said shank having cooperating 80 clutch faces to permit them to be connected and disconnected by the longitudinal movement of said shank, a bracket rigidly secured to said frame and having a bearing, a supporting structure rotatably mounted in said bearing and having a guideway to receive the shank of said handle, said shank being held against rotation relative to said supporting structure, said bracket having an annular cavity surrounding said supporting structure, a clutch ring mounted in said cavity between the circumferential wall thereof and said supporting structure, a clutch member carried by said bracket and cooperating with 85 said clutch ring to prevent the rotation of the same in one direction, and means for frictionally connecting said clutch ring with said supporting structure.

5. In a pump, a frame, a piston actuating device mounted on said frame and comprising a shaft, a handle having a shank, said shaft and said shank having cooperating clutch faces to permit them to be connected and disconnected by the longitudinal movement of said shank, a bracket rigidly secured 90 to said frame and having a bearing, a supporting structure rotatably mounted in said bearing and having a guideway to receive the shank of said handle, said shank being held against rotation relative to said supporting structure, said bracket having an annular cavity surrounding said supporting structure, a clutch ring mounted in said cavity between the circumferential wall thereof and the supporting structure, said bracket having a substantially vertical recess opening into said annular cavity and tapered downwardly, a friction member mounted in said cavity to operate with said friction ring, and means for frictionally connecting said supporting structure with said clutch ring.

6. In a pump, a frame, a piston actuating device mounted on said frame and comprising a shaft, a handle having a shank, said shaft and said shank having cooperating clutch faces to permit them to be connected and disconnected by the longitudinal, movement of said shank, a bracket rigidly secured to said frame and having a bearing, a supporting structure rotatably mounted in said bearing 125

and having a guideway to receive the shank of said handle, said shank being held against rotation relative to said supporting structure, said bracket having an annular cavity surrounding said supporting structure, a clutch ring mounted in said cavity between the circumferential wall thereof and the supporting structure, said bracket having a substantially vertical recess opening into said annular cavity and tapered downwardly, a friction member mounted in said cavity to cooperate with said clutch ring, a series of frictional devices movably mounted on said supporting structure, and springs for pressing said friction devices into engagement with said clutch ring.

7. In a pump, a frame, a piston actuating device mounted on said frame and comprising a shaft, a handle having a shank, said shaft and said shank having cooperating clutch faces to permit them to be connected and disconnected by the longitudinal movement of said shank, a bracket rigidly secured to said frame and having a bearing, a supporting structure rotatably mounted in said bearing and having a guideway to receive the shank of said handle, said shank being held against rotation relative to said supporting structure, said bracket having an annular cavity surrounding said supporting structure, a clutch ring mounted in said cavity between the circumferential wall thereof and the supporting structure, said bracket having a substantially vertical recess opening into said annular cavity and tapered downwardly, a friction member mounted in said cavity to cooperate with said clutch ring, means for frictionally connecting said supporting structure with said clutch ring, and a movable stop to limit the longitudinal movement of the shank of said handle in said supporting structure.

8. In a pump, the combination with a piston actuating device, and a rotatable handle for operating said actuating device, of a device to normally prevent the reverse movement of the handle, the last mentioned device being freely rotatable in a forward direction and comprising a yieldable part to permit such reverse movement of the handle when pressure is applied to the handle in a reverse direction, and means to connect said handle and said last mentioned part with and to disconnect the same from said actuating device.

9. In a pump, the combination with a piston actuating device, and a rotatable handle for operating said actuating device, of a clutch to prevent the reverse movement of said handle, a yieldable connection between said clutch and said handle, and a separable connection between said handle and clutch and said actuating device.

10. In a pump, the combination with a piston actuating device, and a rotatable han-

dle for operating said device, of a device to normally prevent the reverse movement of said handle, the last mentioned device comprising a yieldable part to permit the reverse movement of the handle when pressure is applied to the handle in a reverse direction, and means whereby said handle may be disconnected from said actuating device without releasing said handle from said last mentioned device.

11. In a pump, the combination with a piston actuating device, a rotatable handle, and a separable connection between said handle and said actuating device, of a clutch to prevent the reverse movement of the handle, and a yieldable connection between said clutch and said handle, said handle being capable of movement to disconnect the same from the actuating device without interrupting the yieldable connection between the handle and said clutch.

12. In a pump, the combination with a piston actuating device, and a rotatable handle for operating said actuating device, of a member freely rotatable in a forward direction, a detent to hold said rotatable member against reverse movement, means for so connecting said handle with said rotatable member as to cause the latter to rotate in a forward direction with said handle but to permit said handle to have reverse movement relative to said rotatable member when the latter is held by said detent, and means for connecting said handle and said rotatable member with or disconnecting the same from said actuating device.

13. In a pump, the combination with a piston actuating device, a rotatable handle, and a separable connection between said handle and said actuating device, of a rotatable member, a detent to hold said rotatable member normally against reverse movement, and a frictional connection between said handle and said rotatable member, said handle having a part mounted for axial movement to interrupt said separable connection without interrupting said frictional connection.

14. In a pump, the combination with a piston actuating device, a rotatable handle having a shank, and a separable connection between said shank and said actuating device, of a rotatable supporting member in which said shank is mounted for axial movement, said supporting member and said shank being held against relative rotation, a clutch to prevent the rotation of said supporting member in one direction, and a yieldable connection between said supporting member and one member of said clutch.

15. In a pump the combination with a piston actuating device, a rotatable handle, and a connection between said handle and said actuating device, of a rotatable member separate from said actuating device and connected with said handle, said handle and said

rotatable member being normally held against relative rotation, a clutch to prevent the rotation of said rotatable member in a reverse direction, and a yieldable connection 5 between said rotatable member and one member of said clutch.

In testimony whereof, I affix my signature hereto.

EARL E. EICKMEYER.
